SOFA BED

Walter O. McDaniel, Jefferson, Wis.

Application May 10, 1950, Serial No. 161,221

2 Claims. (Cl. 5—44)

1

This invention appertains to bed davenports and like dual purpose furniture, and more particularly to a davenport which can be readily opened to a full sized comfortable bed, and which when folded will present an attractive, expensive appearing piece of furniture with loose seat cushions.

One of the primary objects of my invention is to provide a tri-section bed davenport, so constructed that the necessity of sleeping on the davenport upholstery is eliminated and one in which the three sections are provided with mattress sleeping surfaces.

Another salient object of the invention is to provide a bed davenport in which the back section is provided with an upholstered reclining front face and a mattress rear face, said back section being pivoted for swinging movement into the davenport frame upon movement of the seat section and intermediate section to an open bed position.

A further object of my invention is to provide novel means for mounting the back section in the frame and for supporting the back section in a firm manner in its horizontal bed position.

A further important object of the invention is to provide means for hingedly connecting the intermediate section directly to the front board or rail of the davenport frame, whereby the said intermediate section as well as the front section moves entirely forward of the frame when in their open bed position to permit a relatively large back section to be utilized, the construction being such as to permit the front section to be provided with a rolled, ornamental edge and removable seat cushions.

A still further object of the invention is to provide novel means for supporting the front and intermediate sections on the frame, when the sections are in their folded seat position.

A still further object of the invention consists in the provision of a simple, efficient and inexpensive method of constructing a dual purpose davenport, wherein the same can be used in the daytime as a luxuriant davenport for sitting and reclining, and at night time as a bed, with a full sized inner spring mattress.

With these and other objects in view, the invention consists in the novel construction, arrangement and formation of parts, as will be hereinafter more specifically described and claimed, and illustrated in the accompanying drawings, in which drawings,

Figure 1 is a transverse sectional view through my improved bed davenport taken on the line

1—1 of Figure 2, looking in the direction of the arrows, the back, seat and intermediate sections being shown in end elevation, with parts thereof broken away and in section to illustrate the mattress.

Figure 2 is a longitudinal sectional view through the bed davenport taken on the line 2—2 of Figure 1, looking in the direction of the arrows.

Figure 3 is a sectional view through the bed davenport, taken on the line 3—3 of Figure 4, looking in the direction of the arrows and showing the same in its open bed position, the mattress being shown carried by the sections in this view.

Figure 4 is a horizontal sectional view taken on the line 4—4 of Figure 3, looking in the direction of the arrows.

Figure 5 is an enlarged fragmentary detail sectional view taken on the line 5—5 of Figure 1, looking in the direction of the arrows and illustrating the stops for limiting the rearward swinging movement of the back section, when the same is being used as a davenport.

Figure 6 is an enlarged fragmentary detail vertical section, taken on the line 6—6 of Figure 1, looking in the direction of the arrows illustrating the hinged connection between the seat and intermediate sections and the means for supporting said sections in their seat position.

Referring to the drawings in detail, wherein similar reference characters designate corresponding parts throughout the several views, the letter F generally indicates my improved dual purpose piece of furniture and the same includes a frame 11 for receiving and supporting a back section 12, a front or seat section 13 and the intermediate section 14.

The frame 11, includes end arm frame members 15 and 16. Each arm frame member includes front and rear uprights or boards 17 and 18, united at their upper ends by an arm rest 19, which can be of an ornamental character, if preferred. The front and rear pieces 17 and 18 are also rigidly united adjacent to their lower ends by side panels 20. These side panels 20 are preferably flush with the inner sides of the front and rear uprights or boards 17 and 18. Rigidly secured to the inner faces of the panels 20 are angle bars for supports 21, the purpose of which will later appear. It is to be noted, however, that the angle bars are arranged adjacent to the lower edges of the panels and are firmly secured thereto by wood screws 22, or the like.

The arm frame members 15 and 16 are rigidly connected together the desired distance apart

by a front flat rail 23, and a rear rail 24. The front rail 23, extends above the rear rail 24, and forms a support for the sections 13 and 14, as will later appear. If desired, the lower ends of the front uprights 17 of the frame members can be provided with ornamental feet 25.

Each of the sections 12, 13 and 14 include a rigid frame 26. These frames can be constructed in any desired way to form a rigid structure and as illustrated each includes spaced parallel longitudinally extending rails 27 and end connecting rails 28. Intermediate transverse brace rails 29 can also be provided and the entire frame is also braced at the corners. The front section 13 and the intermediate section 14 have rigidly secured thereto mattresses 30 and these mattresses are preferably of the inner spring type and their outer faces are covered with suitable mattress ticking.

The frame 26 of the back section 12, is provided with two faces, and one face, i. e., the rear face when the back section is in an upright position, is provided with a mattress section 31, which is also preferably of the inner spring construction. The normal front face of the frame 26 carries an upholstered davenport cushion 32 and this cushion terminates short of the normal lower edge of the back section, as can be best seen in Figure 1, of the drawings.

The back section adjacent to its normal lower end is pivotally connected to the side boards 20 of the end arm frames 15 and 16, adjacent to the rear ends of these arm frames. As illustrated, the side boards or rails 20 have rigidly secured thereto pivot brackets or fixtures 33 and the frame 26 of the back section 12, has rigidly secured to its front face, pivot brackets 34 and pivot pins 35 connect the brackets 33 and 34 together. Consequently, the back section 12, can be pulled forwardly and swung down into the frame 11 when the front and intermediate sections are swung forwardly and out of the frame. When the back section is swung down into the frame, the mattress 31 is uppermost and means is provided for holding this frame in a substantially horizontal position. This means can consist of pivoted legs 36 carried by the sides of the frame 26 of the section 12. As illustrated, the legs 36 are pivoted as at 37 to brackets 38 which are rigidly fastened to the sides of the frame. Stops 39 are carried by the brackets which limit the forward swinging movement of the legs. When the legs are swung at right angles to the frame of the back section, said legs will engage and rest on the angle bars 21, and consequently, the section 12 will be firmly held in its horizontal position.

When the back section is swung back to its normal davenport sitting position, the same is held in its upright position by inwardly extending stop pins 40 carried by the arm frames 15 and 16 and these stop pins are arranged in the path of the rearward swinging movement of the back rest and the brackets 38 engage said pins and effectively hold the back rest in its upright inclined position.

The front and intermediate sections are connected to the main frame 11 in a novel manner and hinges 41 connect the frame of the intermediate section to the inner face of the front rail 23 of the frame 11, adjacent to its upper edge and hence this intermediate section can be swung on its hinges up and then forwardly out of the frame 11 with the bottom thereof resting upon the upper edge of the front rail 23, as is clearly shown in Figure 3 of the drawings. The frames

26 of the front section 13 and the intermediate section 14 are pivotally connected together by knuckle hinges 42 and it is to be noted by referring to Figure 3, that when the sections are in their open forward bed position that the sections 43 and 44 of the hinges abut, so that these sections will be maintained in a horizontal position.

By referring to Figure 1, it can be seen that when the davenport bed is in its set up position for sitting, that the intermediate section 14 is swung down into the frame 11 and that the mattress portion thereof is lowermost. Various means can be provided for holding this section in the frame 11 and off of the floor. As illustrated, the hinge leaves 44 of the hinges 42 have secured thereto legs 45 and these legs are adapted to rest on the angle bars 21 when this section is in its folded position. This is also clearly shown in Figure 1. The front section 13 lies over the intermediate section and the front edge of this section rests upon the upper edge of the front rail 23.

The davenport bed is so constructed, as heretofore brought out, that persons do not sit upon the mattress parts of the sections and by utilizing this novel construction the sections 13 and 14 fit low within the frame and upholstered cushions 46 can be placed upon the upper face of the section 13. Obviously, these seat cushions are removed when the davenport is to be used as a bed. To give a desired finishing effect, the frame 26 of the section 13 can have rigidly secured thereto an ornamental upstanding upholstered board 47, which gives a rolled edge appearance to the davenport and this part 47 also acts as a stop for the seat cushions 46.

When the davenport is opened into a bed, as shown in Figures 3 and 4, the sections 13 and 14 are supported at their front by legs 43. These legs are pivotally connected adjacent to their upper ends to the frame 26 of the section 13 by pivot pins 49 and these pivot pins are carried by brackets 50, which are rigidly secured to the frame of the front section. The legs extend above the frame of the front section and have pivotally connected thereto as at 51 operating links 52. The inner ends of these links are in turn, pivotally connected as at 53, to the hinge leaves 43 of the hinges 42. As the section 13 is pulled forwardly and the section 14 swings into a room, the connecting links 52 will be pulled rearwardly so as to swing the legs 43 to their vertical positions. In the reverse action, when the section 13 is swung up and rearwardly, a forward push will be exerted on the upper ends of the legs and the lower ends of the legs will be swung inwardly. This position is best shown in Figure 1.

In use of the davenport bed, to open the same, it is merely necessary to first remove the seat cushions 46 and to then grasp the finishing board 47, or other convenient part of the front section, and pull up and forwardly on the same, so as to swing the intermediate section 14 on its hinges 41. The front section 13 and the intermediate section 14 will now automatically swing to a horizontal position and the legs 43 will swing to their vertical position. The sections 13 and 14 will then be firmly supported in the manner heretofore described. The back section 12 is now grasped adjacent to the upper end thereof and for swinging downwardly and forwardly into the frame in rear of the intermediate section 14, and as this is done the legs 36 are swung on their pivots until the

same abut the stop pins 39. When the legs 36 engage the angle bars 21, the back section 12 will be in its horizontal position with its mattress uppermost, and its upholstered face 32 lowermost. The bed linen and blankets can now be placed on the mattress face of the sections and a full sized double bed will be had, with a complete inner spring mattress.

In closing the davenport so that the same can be used for sitting and reclining, the back section 12 can be grasped adjacent to its front or upper end and this back section is swung bodily upwardly and rearwardly on the hinge pins 35 until the brackets 38 abut the stop pins 40. The front or seat section 13 is now grasped and the sections 13 and 14 are swung on the hinges 41 and when a desired height is reached, the section 13 is moved down slightly so as to break the hinges 42, after which the section 14 will continue its swinging movement into the frame and the section 13 will follow and rest on top thereof. The seat cushions 46 can now be replaced and the desired good appearing davenport will be had.

From the foregoing description, it can be seen that I have provided a bed davenport which can be easily and quickly operated by a housewife, and one in which when open, the same will form a complete bed with flat mattress sections having their facing ends in close relation and one in which the davenport upholstery is not utilized for sleeping purposes.

Changes in detail may be made without departing from the spirit or the scope of this invention, but what I claim as new is:

1. A combination davenport and bed comprising a main frame including side rails and connecting front and rear rails, a back section, a seat section and an intermediate section associated with the frame, means hingedly connecting the adjacent ends of the seat and intermediate sections together for swinging movement in one position one upon the top of the other, hinges connecting the extreme edge of the intermediate section to the front rail adjacent to the upper portion thereof, whereby the seat and intermediate sections can be swung into the frame, said

frame being provided with horizontally disposed angle bar rests, means hingedly connecting the back section to the frame adjacent to its lower end for swinging movement to and from an upright position into the frame, and legs on the back section for engaging said angle bar rests when the back section is swung into the frame.

2. A combination davenport and bed comprising a main frame including side rails and connecting front and rear rails, a back section, a seat section and an intermediate section associated with the frame, means hingedly connecting the adjacent ends of the seat and intermediate sections together for swinging movement in one position one upon the top of the other, hinges connecting the extreme edge of the intermediate section to the front rail adjacent to the upper portion thereof, whereby the seat and intermediate sections can be swung into the frame, said frame being provided with horizontally disposed angle bar rests, means hingedly connecting the back section to the frame adjacent to its lower end for swinging movement to and from an upright position into the frame, and legs on the back section for engaging said angle bar rests when the back section is swung into the frame, and said front section having legs adapted to engage said angle bar rests when the back section is swung to an upright position and when said seat and intermediate sections are swung into the frame.

WALTER O. McDANIEL.
